W. T. LAZAR,
DISPENSING CONTAINER,
APPLICATION FILED MAY 21, 1919.

1,331,112.

Patented Feb. 17, 1920.

UNITED STATES PATENT OFFICE.

WILLIAM T. LAZAR, OF APPLETON, WISCONSIN.

DISPENSING-CONTAINER.

1,331,112.

Specification of Letters Patent. Patented Feb. 17, 1920.

Application filed May 21, 1919. Serial No. 299,035.

To all whom it may concern:

Be it known that I, WILLIAM T. LAZAR, a citizen of the United States, residing at Appleton, in the county of Outagamie and 5 State of Wisconsin, have invented a new and useful Improvement in Dispensing-Containers, of which the following is a specification.

My invention relates to improvements in 10 containers for dispensing interleaved paper napkins, towels and the like wherein hingedly connected and matching semi-cylindrical portions operate to form a closed container having a longitudinal dispensing slot 15 formed therein by matching of longitudinally disposed recesses in the free ends or edges of said matching semi-cylindrical portions.

The primary object of the present invention is to provide an improved dispensing container having improved means for the placing and threading of an interleaved paper napkin or towel package.

A still further object of the present invention is to provide an improved container of 25 the character described having improved means for supporting an interleaved package of extremely thin and flexible paper napkins in such a position above a dispensing slot that said napkins or the like may be detached from the package and singly dispensed through said slot without disturbing the remaining napkins or packages.

Other objects and advantages will herein- 30 after more fully appear.

I accomplish these and several objects by means of the device disclosed in the drawings forming a part of the present specification wherein like characters of reference are 40 used to designate similar parts throughout the said specification and drawings, and in which:

Figure 1 is a vertical sectional view of the 45 container in an open or receiving position; Fig. 2 is a broken front elevation of Fig. 1 with the paper napkin package removed;

Fig. 3 is a transverse vertical sectional view of the container in a closed position; and

50 Fig. 4 is an end elevation disclosing one method by means of which the matching portions of the container may be locked together.

The present invention is an improvement 55 over Patent No. 1,228,571 issued to me on the

5th day of June, 1917, in which patent a dispensing container for dispensing leaves from an interleaved package is provided with means, in the form of struck up lugs, for imparting a slight arch or curvature to the 60 bottom of the interleaved package. This type of container is well adapted for the heavier and more rigid types of paper, such as interleaved paper towels and the like.

But, I find from experience, that the thinner and more flexible packages comprising thin tissue paper napkins and the like will collapse when only slightly arched above the dispensing slot. Therefore, I have provided the present improvement which is adapted 70 to retain a package of extremely thin interleaved tissue paper napkins in a circular position and against the internal surface of a hollow cylindrical container which may be described as follows:

Referring to the drawings the numeral 1 is used to designate a hollow cylindrical container comprising hollow semi-cylindrical portions 2 and 3 each portion being hingedly connected at one longitudinal edge 80 thereof to a longitudinal edge of the other portion as at 4. The edge of each portion 2 and 3 opposite the hingedly connected edges is provided with a recess 6 and 7 respectively which match to form a longitudinal slot 8 85 when the portions 2 and 3 are closed as disclosed in Fig. 3 of the drawings.

The recesses 6 and 7 are formed by projecting inwardly a portion of the outer walls or periphery of the portions 2 and 3 respectively to form inwardly projecting flanges 9 and 10 respectively.

The ends of each portion 2 and 3 are also provided with outwardly extending flanges 11 and 12 respectively which are arranged 95 to match or lie adjacent or upon each other when the portions 2 and 3 are closed as disclosed in Fig. 4 of the drawings. The flanges 11 are provided with projecting pins 13 adapted for engagement with apertures 100 14 within the flanges 12 by means of which the portions 2 and 3 may be aligned to form a hollow cylindrical container when said portions are closed one upon the other as disclosed in Figs. 3 and 4 of the drawings.

Each flange 11 is likewise provided with a pivotally mounted latch 16 having a return bend or portion 17, which forms a U-shaped portion to engage and lock together the flanges 11 and 12 and thereby 110

lock or retain the container 1 in a closed position.

However, it should be understood that any suitable locking device may be employed to retain the portions 2 and 3 in a closed position without departing from the spirit of the invention.

In placing a pile or package 18 of interleaved paper napkins within the container 10 the same is opened as disclosed in Figs. 1 10 and 2 of the drawings. In this open position the container may be placed horizontally or vertically to suit the convenience of the operator.

15 The package 18 of interleaved flexible tissue paper napkins is placed with the approximate longitudinal center thereof over the hinge 4 and the longitudinal edges of said package 18 are moved within each respective portion 2 and 3 and behind their 20 respective inwardly projecting flanges 9 and 10 with one free edge of one of the paper napkins extending over one of said flanges as disclosed in Fig. 1 of the drawings.

25 By closing the portions 2 and 3 upon each other the free end of the napkin is left projecting through the slot 8 and the package 18 is then bent or formed into a circular position adjacent the internal surface of the 30 container 1 as disclosed in Fig. 3 of the drawings.

The latches 16 are then moved to cause the U-shaped or return portions 17 thereof to engage the outwardly projecting flanges 35 11 and 12 on the ends of the portions 2 and 3 respectively, which engagement, in conjunction with the engagement of the pins 13 of the flanges 11 with the apertures 14 of the flanges 12 will aline said portions 2 40 and 3 and retain them in a closed position.

The paper napkins are then withdrawn singly through the slot 8 in the usual and well known manner.

It is obvious from the foregoing that I 45 have provided a new and improved container for dispensing thin tissue paper napkins from an interleaved package and supporting such package above a dispensing slot in a manner that said napkins may be 50 readily and easily dispensed through said slot without disturbing the remaining towels or the position of the package 18.

It is also evident that I have provided a new and improved means for placing and 55 threading a package of interleaved paper napkins within a dispensing container.

If desired the hinge 4 may be dispensed with as the halves of the container need only be alined when closed and this alinement is effected and retained by the engagement of the pins 13 with the apertures 14 60 operating in conjunction with suitable locking means for holding the halves 2 and 3 together, such as the latch 16 or its mechanical equivalent.

Having thus described my invention, what I claim as new and desire to secure by Letters Patent is:

1. A dispensing container comprising hollow portions each hingedly connected at one longitudinal edge to the other portion and likewise provided with a longitudinal recess on the longitudinal edges opposing said hingedly connected edges, said recesses matching, when the container is closed, to 70 form a longitudinally disposed slot in said container through which napkins from an interleaved package within said container may be dispensed; and means arranged adjacent each recess to engage the longitudinal 75 edges of and thereby retain said interleaved package in an arched position within the container and above the slot therein.

2. A dispensing container comprising hollow portions each hingedly connected at one 80 longitudinal edge to the other portion and likewise provided with a longitudinal recess on the longitudinal edges opposing said hingedly connected edges, said recesses matching, when the container is closed, to 85 form a longitudinally disposed slot in said container through which napkins from an interleaved package within said container may be dispensed; means arranged adjacent each recess to engage the longitudinal edges of 90 and thereby retain said interleaved package in an arched position within the container and above the slot therein; and means for 95 engaging and locking the portions in a closed position to form a hollow cylindrical 100 container having a longitudinal slot therein.

3. A dispensing container comprising hollow portions each hingedly connected at one longitudinal edge to the other portion and likewise provided with a longitudinal recess on the longitudinal edges opposing said hingedly connected edges, said recesses matching, when the container is closed, to 105 form a longitudinally disposed slot in said container through which napkins from an interleaved package within said container may be dispensed; and means arranged adjacent each recess to engage the longitudinal edges of 110 and thereby retain said interleaved package in an arched position within the container and above the slot therein; and a latch arranged on each end of one portion and adapted for engagement with the other portion to lock said portions in a closed 115 position.

4. A dispensing container adapted for dispensing interleaved paper napkins and the like comprising a pair of hollow portions hingedly connected at one longitudinal edge and each having a recess on the opposite longitudinal edge thereof whereby a container having a longitudinal slot therein, formed of the matching recesses, may be provided when said portions are closed; an inwardly projecting flange arranged adja- 120 125 130

cent each recess to engage the longitudinal edges of and thereby retain an interleaved paper package in an arched position within said container and above the slot formed 5 therein; outwardly projecting flanges on each end of each portion; and a latch pivotally mounted upon each flange of one portion and arranged to engage the flanges of the other portion to lock said portions in a 10 closed position.

5. A dispensing container adapted for dispensing interleaved paper napkins and the like comprising a pair of hollow portions hingedly connected at one longitudinal 15 edge and each having a recess on the opposite longitudinal edge thereof whereby a container having a longitudinal slot therein, formed of the matching recesses, may be provided when said portions are closed; an 20 inwardly projecting flange arranged adjacent each recess to engage the longitudinal edges of and thereby retain an interleaved paper package in an arched position within said container and above the slot formed 25 therein; outwardly projecting flanges on each end of each portion; a latch pivotally mounted upon each flange of one portion and arranged to engage the flanges of the other portion to lock said portions in a 30 closed position; and means for retaining the portions in a properly matched position when closed.

6. A dispensing container adapted for dispensing interleaved paper napkins and the like comprising a pair of matching hollow semi-cylindrical members hingedly connected at one longitudinal edge and provided at each opposed longitudinal edge 35 with a longitudinally disposed recess, said 40 recesses being adapted to form a longitudinal slot when said portions are closed to form a cylinder; inwardly projecting flanges arranged adjacent to each recess to engage the longitudinal edges of, and thereby retain in an arched position, an interleaved paper napkin package; an outwardly 45 projecting flange arranged on the end edges of each member, said outwardly projecting flanges being arranged to lie one upon the other when the semi-cylindrical portions are 50 closed; one flange on each end being provided with an aperture; a pin on each other flange arranged to engage the aperture in the opposite flange to aline the semi-cylindrical portions; and a latch pivotally mounted upon the outwardly projecting flanges of one portion and arranged to engage the flanges of the other member to retain said 55 portions in a closed position.

7. A dispensing container adapted for

dispensing interleaved paper napkins and the like comprising a pair of matching hollow semi-cylindrical members hingedly connected at one longitudinal edge and provided at each opposed longitudinal edge 60 with a longitudinally disposed recess, said recesses being adapted to form a longitudinal slot when said portions are closed to form a cylinder; inwardly projecting flanges arranged adjacent to each recess to engage the longitudinal edges of, and thereby retain in an arched position, an interleaved paper napkin package; an outwardly 65 projecting flange arranged on the end edges of each member, said outwardly projecting flanges being arranged to lie one upon the other when the semi-cylindrical portions are closed, one flange on each end being provided with an aperture; a pin on each other 70 flange arranged to engage the aperture in the opposite flange to aline the semi-cylindrical portions; and means pivotally connected to one set of outwardly extending flanges and adapted to engage the other set 75 to retain the semi-cylindrical portions in a closed position.

8. A dispensing container adapted for dispensing interleaved paper napkins and the like comprising a pair of matching hollow semi-cylindrical members hingedly connected at one longitudinal edge and provided at each opposed longitudinal edge 80 with a longitudinally disposed recess, said recesses being adapted to form a longitudinal slot when said portions are closed to form a cylinder; inwardly projecting flanges arranged adjacent to each recess to engage the longitudinal edges of, and thereby retain in an arched position, an interleaved paper napkin package; an outwardly 85 projecting flange arranged on the end edges of each member, said outwardly projecting flanges being arranged to lie one upon the other when the semi-cylindrical portions are 90 closed; one flange on each end being provided with an aperture; a pin on each other flange arranged to engage the aperture in the opposite flange to aline the semi-cylindrical portions; and a latch pivotally mounted upon the outwardly projecting flanges of one portion and arranged to engage the flanges of the other member to retain said 95 portions in a closed position.

In witness whereof I hereunto set my signature.

WILLIAM T. LAZAR.
